CIRCUIT-BREAKER MECHANISM

Alfred J. A. Peterson and John B. MacNeill, Wilkinsburg, and Andrew H. Bakken, Pittsburgh, Pa., assignors to Westinghouse Electric & Manufacturing Company, East Pittsburgh, Pa., a corporation of Pennsylvania

Application December 29, 1939, Serial No. 311,652

23 Claims. (Cl. 200—50)

Our invention relates to a circuit-breaker linkage or operating-mechanism which has been specially designed for circuit-breakers comprising an arc-extinguishing switching-member, a serially connected disconnecting switching-member, and a relatively high-current-capacity switching-member adapted to be connected in parallel-circuit relation to the two serially connected switching-members. Our invention was particularly designed for water breakers, or breakers in which the arc-extinguishing contact is broken in water, utilizing the water vapor and the gaseous products of water-dissociation to extinguish the arc, although our invention is applicable also to other types of breakers in which the arc-extinguishing function is performed in some medium other than water, such, for example, as in oil or compressed air.

Our invention has particular applicability to those breakers, in general, in which the arc-extinguishing function is performed in a medium or structure of such nature that it is desired to open a serially connected disconnect-switch after the arc-extinguishing contacts have been substantially fully opened, and in which it is desirable to close the arc-extinguishing contacts before the full line-voltage is applied thereto by the closure of the disconnect-switch. In this class of breakers, the final opening of the disconnect-switch, as the last step in the opening of the breaker, serves to remove the line-voltage from the arcing chamber, thus making it possible to design said chamber in an economical manner having no relation to the necessity for constantly and continuously withstanding the full line-voltage with practically no current-leakage.

The operation of closing the arc-extinguishing contacts while the disconnect-switch is still open, that is, while no voltage is being applied to the terminals of the arc-extinguishing contacts, avoids the possibility of the premature striking of an arc across the arc-extinguishing contacts as they are approaching each other in the closing-operation, as such premature or temporary striking of an arc would produce very undesirable turbulence in the arc-quenching chamber, and would also very much weaken the efficacy of the arc-quenching properties of the breaker in the event that it should be necessary to immediately reopen the breaker, because of some faulty condition in the line in which the breaker is connected.

The parallel-connected by-passing-contact of high current-capacity is desirable in many instances, notably in breakers of the higher cur-

rent-ratings, in order to relieve the arc-extinguishing or current-interrupting contacts of all but temporary duty during the circuit-closing and circuit-opening operations, the major portion of the current being normally carried by the by-passing contacts.

The principal object of our invention is to provide an improved operating-mechanism linkage for operating a circuit breaker of the type just described.

A more specific object of our invention is to provide an air-break member or disconnect-switch which is operated, with a snap-action, from the operating-mechanism linkage of the circuit-breaker as a whole, either with a toggle-spring mechanism for opening or closing the disconnect-switch near the ends of the opening and closing operations of the linkage, respectively, or with holding-latches, or their equivalent, for holding the disconnect-switch in either or both of its open and closed positions, until such time as the holding-latches are released by the movement of the operating-mechanism linkage, the closed-disconnect latch being preferably a multi-notched latch, or the equivalent, for holding the disconnect-switch in any one of a plurality of closed positions of different degrees of closure. The disconnect-switch may also have a positive thrust imparted to the same, either as an aid to, or as a substitute for, the toggle-spring mechanism, by means of rollers or bumpers carried by the operating-mechanism linkage, for opening or closing the disconnect-switch near the latter part of the movement of the linkage in either the opening or closing direction, respectively.

A further object of our invention, in breakers which are provided with a parallel-connected main switch of heavy current-carrying capacity, is to provide a toggle-mechanism, or equivalent mechanical-motion means, between the operating mechanism and the linkage of our invention, whereby a relatively large movement of the operating mechanism is accompanied by a relatively small movement of the arc-extinguishing switching-member when the latter is in its fully closed position, so that the operating mechanism can continue to close, through a considerable distance of motion, after the arc-extinguishing contacts have closed, this final closing movement of the mechanism being utilized to close the main contacts, and contrary-wise, during the opening movement of the mechanism, the initial movement of the mechanism being utilized to open the main contacts, while the arc extin-

guishing contacts scarcely move at all, and at first remain closed.

With the foregoing and other objects in view, our invention consists in the systems, combinations, mechanisms, parts and processes herein-after described and claimed, and illustrated in the accompanying drawing, wherein:

Figure 1 is a diagrammatic view showing our improved breaker, and the operating mechanism and linkage therefor, in a diagrammatic manner, not to scale, but with a view to the illustration of the essential operative principles of the very complicated mechanism and linkage which is necessary in any practical embodiment of our invention, as will be readily understood by those who are familiar with circuit-breaker mechanisms. Fig. 1 shows the operating mechanism and the novel linkage of our invention, with the three different contact-members of the circuit-breaker in their closed positions, while Fig. 2 is a similar view of the linkage-part alone, showing the switching-members of the circuit breaker in their open positions.

We have illustrated our invention in connection with a circuit-breaker having three switching-members designated, in their entireties, at 1, 2 and 3, respectively.

The switching-member 1 is the arc-extinguishing member of the combination, or the point at which the arc is finally extinguished, in the circuit-opening operation of the breaker as a whole. Although, as previously pointed out, we are not limited to any particular kind of arc-extinguishing switching-member 1, we have diagrammatically illustrated this member, for the sake of fixing our ideas and showing something definite, as a water-break circuit-breaker in which the stationary contacts 4 are immersed in water 5 which is held within a suitable container 6, the stationary contacts 4 being adapted to be bridged by a movable contact 7. There are, on the market, several different forms of switching-members utilizing water as the arc-extinguishing medium, and a number of these have been described in the technical press, so that we have not deemed it necessary to illustrate and describe the precise details of any preferred form of water-break apparatus, but have merely diagrammatically designated such an apparatus in the drawing.

The switching-member 2 is an open-air disconnect-switch which is electrically connected in series with the arc-extinguishing switching member 1. Physically, the disconnecting switching-member 2 comprises a pivoted switch-arm 8, pivoted at 9, and terminating in a contact-blade 10 which cooperates with a bifurcated stationary contact-member 12.

The switching-member 3, when utilized, is the main current-carrying member which is electrically connected in shunt across the two serially-connected switching-members 1 and 2. It is made of very massive parts, comprising a movable switch-arm 13 which is pivoted at 14, and a bifurcated stationary contact-member 15.

Any suitable operating-mechanism may be utilized to operate our circuit-breaker. Although our invention is not limited to any particular type of operating mechanism, we have shown, by way of preference, a typical trip-free operating mechanism 20, which may be described as comprising an operating-link 21 which joins the switch-arm 13 to one end of an outer lever 22 which is intermediately pivoted at 23. The outer lever 22 has a second extending end 24, carrying a tripping-latch pin 25. Mounted upon the same pivot-pin 25

as the outer lever 22, is an inner lever 26, one end of which is connected to a retrieving spring 27, while the other end carries a latch-pivot 28 which supports a tripping-latch 29 for engaging the latch-pin 25 carried by the outer lever 22. The tripping-latch 29 is provided with an outwardly extending arm or tripping lever 31, which is adapted to be elevated, in order to trip the mechanism, as by means of a trip-coil 32 and a cooperating armature or core 33 for raising a trip-pin 34 into engagement with the tripping lever 31.

The inner lever 26 is provided with a retrieving pin 36 which is fastened to said inner lever 26 at a point intermediate between the pivotal point 23 and the latch-pivot 28. The retrieving pin 36 engages within an eye-bolt 37 which is carried by the armature or core 33 of a closing-magnet 39.

The inner lever 26 is also provided with a main latch-pin 41 which is shown in a position intermediate between the retrieving pin 36 and the latch-pivot 28. The main latch-pin 41 is adapted to be engaged by a main latch 42 which is stationarily pivoted at 43, and which is normally biased toward its latching position, as by means of a compressing-spring 44. The main latch 42 has an outwardly extending operating-arm 45 which is adapted to be actuated by an abutment or projection 46, which is carried by the outer lever 22, and which moves into engagement with the latch-arm 45 when the mechanism moves away from its closed position which is illustrated in Fig. 1.

Our invention relates to a novel form of linkage for utilizing any suitable operating mechanism such as the mechanism 20 which has just been described, and which is diagrammatically indicated in Fig. 1. In the illustrated form of embodiment of our invention, the operating link 21 of the operating mechanism is connected to the movable arm 13 of the main switching-member 3, being pivoted thereto at an intermediate point 50 thereof. The said movable arm 13 of the main switching-member 3 is also illustrated as being provided with a powerful opening-spring 51.

In the illustrated embodiment of our invention, the pivoted arm 13 of the main switching member 3 is provided with a projecting extension 52 carrying a pivot-pin 53 which is displaced out of the plane of the switching arm 13, so as to operate, in effect, something like a bell-crank arm with respect to the pivot-point 14, as indicated by the dotted line 54. The bell-crank pivot-pin 53 is connected, by a link 55, to a projecting arm 56 of a complicated lever-mechanism 57 which is stationarily pivoted at 58. The lever-mechanism 57 has a second arm 59 which is pivoted, at 61, to an intermediate point in a walking-beam 62 which operates to lift-rod 63 of the arc-extinguishing switching-member 1, the lower end of the lift-rod 63 carrying the movable contact-member 10 of said switching-member.

The lever-mechanism 57 is also provided with a third extending arm 65 which terminates in a pin 66 to which is attached one end of a toggle-spring 67, the other end of which is connected to an intermediate point 68 in the pivoted arm 8 of the disconnecting switching-member 2. The extending arm 65 of the lever-member 57 operates in what we call a toggle fashion, to swing the end 66 of the toggle-spring 67 from one side, to the other, of the disconnect-arm 8, when the lever-member 57 is moved from its breaker-closed position to its breaker-open position, in a manner which will be more fully described hereinafter.

We also preferably provide our disconnect-arm

8 with a pair of latching-members 70 and 71, which are stationarily pivoted at 72. When the disconnect-arm 8 is open, an intermediate pin 73, which is carried thereby, is engaged by the latch 70, to hold the disconnect-arm 8 open, while, when the disconnect-arm 8 is closed, its holding-pin 73 will be engaged by any one of a plurality of notches or detents 74 of the latching-member 71, it being understood that the latching-members 70 and 71 are so offset that their latching points can engage the holding-pin 73 of the disconnect-arm 8, while the latch-pivot 72 is out of the path of the holding-pin 73 so as not to interfere with the swinging movement of the disconnect-arm 8.

We usually prefer to provide a plurality of notches 74 on the closed-disconnect latching-means 71 so as to more effectively hold the disconnect-arm 8 against rebounding, either from the mechanical forces involved, or because of the electrical forces developed by the current flowing through the disconnect-contacts 11 and 12, and also for the more important purpose of holding the disconnect-arm 8 either fully closed, with its movable contact-member 11 fully inserted into the bifurcated stationary contact-member 12, as in the normal operation of the device, or only partially closed, in case a breaker-opening operation should be instantly initiated as soon as the movable disconnect-contact 11 began to touch the stationary disconnect-contact 12. This precaution is taken in order that these contacts 11 and 12 will not possibly prematurely open, prior to the opening of the arc-extinguishing contacts 6 and 7, as will be subsequently described more fully.

The latching members 70 and 71 are also provided with actuating arms 76 and 77, respectively, which are adapted to be engaged by an unlatching arm 78, which is carried by the lever-mechanism 57, so that the respective latches 70 and 71 are disengaged from the holding-pin 73 of the disconnect-arm 8, at an appropriate time during the operation of the lever-member 57, as will be subsequently described.

In accordance with our invention, we further prefer to equip the lever-mechanism 57 with thrust-members or rollers 80 and 81 for cooperation with the disconnect-arm 8. The thrust-roller 80 of the lever-member 57, which is a part of our operating-mechanism linkage, engages the disconnect arm 8, at an appropriate point in the closing-movement of the linkage, to supplement the action of the toggle-spring 67 by giving the disconnect-arm 8 a positive thrust in the closing direction, while the thrust roller 81 performs a similar function during the opening operation, as will be subsequently described.

In operation, assuming that the circuit-breaker is closed, as shown in Fig. 1, it will be noted that the main current is carried, say from the line 85, through the main contacts 15 and 13, to the line 86. Only a relatively small part of the total current is carried through the shunt-path through the disconnect-switch contacts 12 and 11, and the arc-extinguishing contacts 7 and 4. In order to carry this current, a flexible pigtail shunt 87 is preferably provided, to connect the disconnect-arm 8 and the lift-rod 63 of the arc-extinguishing switching-member 1.

A circuit-opening operation is initiated by the elevation of the tripping-lever 31, as by the energization of the trip-coil 32. This disengages the tripping latch 29 from the latch-pin 25 of the outer lever 22, and leaves said outer lever free

to swing clockwise, about its pivotal point 23, by reason of the downward thrust of the operating link 21 as a result of the strong pull of the opening-spring 51. For convenience in description, we shall first follow through the operation of the operating mechanism 20 and then go back and follow through the operation of our novel linkage which is associated with the main switch-arm 13.

When the outer lever 22 of the operating mechanism swings open, in a clockwise direction, its latch-actuating projection 46 engages the actuating-arm 45 of the main latch 42, disengaging said latch from the latch-pin 41 carried by the inner lever 26, and permitting said inner lever 26 to move, in a clockwise direction, about the pivot pin 23, under the influence of the retrieving spring 27. During this movement of the inner lever, the retrieving pin 36 is elevated, thus raising the armature-core 38 of the closing-magnet 39. When the inner lever 26 completes its clockwise movement, it relatches itself again, to the outer lever 22, through the operation of the tripping latch 29, so that the parts are now ready for a reclosing operation, which will be described later on.

Meanwhile, considering the operation of our novel linkage during the opening movement of the main switch-arm 13, it will be noted that, when the main switch-arm 13 is in its closed position, as shown in Fig. 1, the bell-crank arm 54 and the link 55 are almost in alignment with each other, in toggle fashion, so that a considerable swinging-movement of the main switch-arm 13 will be accompanied by only a slight rocking-movement of the lever-member 57 about its pivot-point 58. The object in this toggle-joint disposition of the parts 54 and 55 is to permit the main contacts 15 and 13 to be well opened or separated before the rocking lever-member 57 has moved far enough to raise the arc-extinguishing moving-contact 7 out of its bridging-relation with respect to the stationary contacts 4 of the arc-extinguishing switching-member 1.

After the main switch-arm 13 is well separated from its stationary contact 15, the toggle 54-55 is broken sufficiently so that the continued opening movement of the main switch-arm 13 rocks the lever-member 57 in a clockwise direction sufficiently to elevate the lift-rod 63 far enough to break the arc-extinguishing contacts between the contact-members 7 and 4, thus drawing an arc which is extinguished in the water 5, or equivalent a r c - extinguishing medium. The opening movement of the mechanism continues until a point is reached at which the arc is extinguished, or practically extinguished, in the arc-extinguishing switching-member 1. Before this point has been reached, in the opening movement of the mechanism, the bottom end 66 of the rocking lever-mechanism 57 will have swung from the right-hand side to the left-hand side of the disconnect-arm 8, so that, whereas, at the beginning of the opening-stroke, the toggle-spring 67 tended to hold the disconnect-arm closed, the bottom end of the toggle-spring 67 has now passed dead-center with respect to the disconnect-arm 8, so that the toggle-spring 67 now tends to open said arm.

After this point is reached, in the opening operation, and when the arc-extinguishing operation is completed, or nearly completed, in the chamber 6, the latch-operating projection 78 of the clockwise-swinging lever-member 57

actuates the closed-disconnect latch or holding-means 71, so as to permit the disconnect-arm 8 to begin to open, under the influence of the toggle-spring 67. Almost immediately thereafter, as the clockwise rotation of the lever-member 57 continues, during the remainder of the opening-movement of the mechanism, the thrust-roller 81 engages the disconnect-arm 8 to supplement the toggle-spring operation by giving the disconnect-arm a positive thrust in the opening direction, thereby considerably facilitating this operation. The final opening-operation is thus completed, at the disconnecting switching-member 2, the contacts of which open with a rapid and positive snap-action, thus insulating the arc-extinguishing chamber 6 from the voltage of the line 85-86. When the disconnect-arm 8 is fully opened, it is latched in its open position, by means of the latch 70, so that during the subsequent closing operation, the disconnect-arm 8 will not prematurely close.

To close the circuit breaker, the closing-magnet 39 is energized, thus pulling down the retrieving pin 36 of the operating mechanism, and since the inner and outer levers 26 and 22 are latched together at 29, this depression of the retrieving pin 36 causes both of the levers 26 and 22 to swing in a counter-clockwise direction about their common pivotal point 23, thus lifting the operating rod 21, and closing the main switch-arm 13.

During the first portion of the lifting-movement of the main switch-arm 13, long before said arm comes into contact with its cooperating stationary contact-member 15, the link 55 swings the lever-member 57 in a counter-clockwise direction, from the position shown in Fig. 2, the first result of said swinging-movement being to close the arc-extinguishing contacts 7 and 4, this operation being completed while the disconnecting switching member 2 is still open, and hence while the line-voltage is kept off of the arc-extinguishing switching-member 1, thus avoiding premature disturbances within the arc-extinguishing chamber 6.

During this counter-clockwise swing-movement of the lever-member 57, the bottom end 66 of the toggle-spring 77 is swung from the left-hand side of the disconnect-arm 8, past dead-center with respect to said arm, and over to the right-hand side of said disconnect-arm 8, so that the toggle-spring 67 now tends to close the disconnect-arm 8, but said arm is latched in its open position, as shown in Fig. 2, by means of the latch 70. When the moving contact 7 of the arc-extinguishing switching-member 1 comes into contact with its cooperating stationary contacts 4, or when it is just about to come into contact therewith, the latch-actuating projection 73 of the counter-clockwise swinging lever-member 57 engages the open-disconnect latch 70 and disengages the same from the latching pin 73 of the disconnect-arm 8, permitting said arm to begin to close, under the influence of the toggle-spring 67. Almost immediately thereafter, however, the thrust-roller 80 of the counter-clockwise swinging lever-member 57 engages the left-hand side of the disconnect-arm 8 and forcibly thrusts it in a closing direction, to expedite the closing-movement of the disconnect-arm 8, with a positive snap-action.

At this point, in the closing operation, when the moving contact 7 of the arc-extinguishing switching member 1 has just begun to move in between the stationary contacts 4, the closing op-

eration of the circuit-breaker mechanism 20 is not yet completed, but the bell-crank arm 54 of the mechanism 13-52 is nearly in alignment, toggle-fashion, with the link 55, so that the continued swinging movement of the closing switch-arm 13 of the main switching-member 3 results in a relatively small, continued wiping-movement of the moving contact 7, as it continues to move, in the closing direction, between the two stationary contacts 4 of the arc-extinguishing switching-member 1. As a result of this toggle-action 54-55, when the arc-extinguishing switching-member 1 is in its fully closed position, we make it possible for the main contact-arm 13 to be well separated from its stationary contact-member 15 at the time when the arc-extinguishing contacts 7 and 4 close and when the disconnecting contact-arm 8 snaps closed, so that the final movement of the closing-operation will finally close the main contacts 13 and 15, thus bypassing the temporary-duty contacts 4, 7, 11 and 12 of the serially-connected switching-members 1 and 2.

While we have illustrated our invention in a preferred form of embodiment, and have explained its mode of operation, particularly in connection with a water-dielectric circuit-breaker, we wish to be understood that it is not necessary, in practicing our invention, to utilize all of the described features at the same time, in any given apparatus, and we wish it to be further understood that various changes, by way of substitutions and additions, may be utilized, without departing from the essential spirit of our invention, particularly in its broader aspects. We further wish it to be understood that the illustrated embodiment is only diagrammatically shown, and that the necessary clearances will be provided so that the various moving parts will clear each other, or contact with each other, as the occasion requires, and as hereinabove described. We desire, accordingly, that the appended claims shall be given the broadest interpretation consistent with their language.

We claim as our invention:

1. A circuit-breaker comprising an arc-extinguishing switching-member, a serially connected disconnecting switching-member, an operating-mechanism for opening and closing said arc-extinguishing switching member, a shiftable toggle-spring support carried by said mechanism, a spring operatively connected between said disconnecting switching-member and said toggle-spring support, and opening and closing means for operating said mechanism, said toggle-spring support being so disposed as to be so shifted, during the operation of said mechanism, that said spring tends to close said disconnecting switching-member when said toggle-spring support is past a dead-center in the closing movement of said mechanism, and said spring tends to open said disconnecting switching-member when said toggle-spring is past a dead-center in the opening movement of said mechanism.

2. A circuit-breaker comprising an arc-extinguishing switching-member, a serially connected disconnecting switching-member, an operating-mechanism for opening and closing said arc-extinguishing switching-member, a disconnect-opening spring-means operable, when said arc-extinguishing switching member is open, to tend to open said disconnecting switching-member, releasable closed-disconnect holding-means for holding said disconnecting switching-member closed against the bias of said disconnect-opening

spring-means, means operable during the opening movement of said mechanism, when said arc-extinguishing switching-member has opened by a predetermined amount, to release said disconnecting switching-member from said closed-disconnect holding-means, and means responsive to the closing movement of said mechanism for causing said disconnecting switching-member to close after the closure of said arc-extinguishing switching-member during the closing movement of said mechanism.

3. A circuit-breaker comprising an arc-extinguishing switching-member, a serially connected disconnecting switching-member, an operating-mechanism for opening and closing said arc-extinguishing switching-member, disconnect-opening spring-means operable, when said arc-extinguishing switching-member is open, to tend to open said disconnecting switching-member, releasable closed-disconnect holding-means for holding said disconnecting switching-member closed, in any one of a plurality of closed positions of different degrees of closure, against the bias of said disconnect-opening spring-means, means operable during the opening movement of said mechanism, when said arc-extinguishing switching-member has opened by a predetermined amount, to release said disconnecting switching-member from said closed-disconnect holding-means, and means responsive to the closing movement of said mechanism for causing said disconnecting switching-member to close after the closure of said arc-extinguishing switching-member during the closing movement of said mechanism.

4. A circuit-breaker comprising an arc-extinguishing switching-member, a serially connected disconnecting switching-member, an operating-mechanism for opening and closing said arc-extinguishing switching-member, disconnect-closing spring-means operable, when said arc-extinguishing switching-member is closed, to tend to close said disconnecting switching-member, releasable open-disconnect holding-means for holding said disconnecting switching-member open against the bias of said disconnect-closing spring-means, means operable during the closing movement of said mechanism, when said arc-extinguishing switching-member has closed, to release said disconnecting switching-member from said open-disconnect holding-means, and means responsive to the opening movement of said mechanism for causing said disconnecting switching-member to open after the opening of said arc-extinguishing switching-member during the opening movement of said mechanism.

5. The invention as defined in claim 1, in combination with releasable open-disconnect holding-means for holding said disconnecting switching-member open, releasable closed-disconnect holding-means for holding said disconnecting switching-member closed, means responsive to the closing movement of said mechanism to release said disconnecting switching-member from said open-disconnect holding-means after said toggle-spring support has been moved past the dead-center in the closing movement of said mechanism, and means responsive to the opening movement of said mechanism to release said disconnecting switching-member from said closed-disconnect holding-means after said toggle-spring support has been moved past the dead-center in the opening movement of said mechanism.

6. A circuit-breaker comprising an arc-extin-

guishing switching-member of a kind such that it is undesirable to leave the circuit-voltage continuously applied thereto after its opening-operation and such that it is undesirable to have the circuit-voltage applied thereto when its switching-contacts are approaching each other during its closing-operation, a serially connected disconnecting switching-member, holding means for holding the disconnecting switching-member both in its open position and in its closed position, respectively, an operating-mechanism for opening and closing said arc-extinguishing switching-member, and means responsive to the movement of said mechanism for operatively engaging the disconnecting switching-member with a sudden striking-movement and for nullifying the holding-action of the holding-means which had been effective on the disconnecting switching-member, when the mechanism is in an intermediate position, both in its closing movement and in its opening movement, whereby the disconnecting switching-member is forcibly moved from one position to the other.

7. A circuit-breaker comprising an arc-extinguishing switching-member of a kind such that it is undesirable to leave the circuit-voltage continuously applied thereto after its opening-operation and such that it is undesirable to have the circuit-voltage applied thereto when its switching-contacts are approaching each other during its closing-operation, a serially connected disconnecting switching-member, an operating-mechanism, means responsive to an early part of the opening movement of said mechanism for initiating a separation of the contacts of said arc-extinguishing switching-member, means responsive to an early part of the closing movement of said mechanism for beginning to close the contacts of said arc-extinguishing switching-member, and lost-motion means responsive to the continued movement of said mechanism, with a lost-motion connection so that the mechanism must first move a considerable distance, in either its opening movement or its closing movement, before said lost-motion means is set into motion, said lost-motion means thereupon belatedly responding to the continued movement of said mechanism for forcibly mechanically actuating the disconnecting switching-member from the mechanism with a delayed snap-action so that the disconnecting switching-member opens with a snap-action after the opening of the arc-extinguishing switching-member during the opening operation of the mechanism, and closes with a snap action after the closure of the arc-extinguishing switching-member during the closing operation of the mechanism.

8. A circuit-breaker comprising an arc-extinguishing switching-member of a kind such that it is undesirable to leave the circuit-voltage continuously applied thereto after its opening-operation and such that it is undesirable to have the circuit-voltage applied thereto when its switching-contacts are approaching each other during its closing-operation, a serially connected disconnecting switching-member, an operating-mechanism, means responsive to an early part of the opening movement of said mechanism for initiating a separation of the contacts of said arc-extinguishing switching-member, means responsive to an early part of the closing movement of said mechanism for beginning to close the contacts of said arc-extinguishing switching-member, and lost-motion means responsive to the continued movement of said mechanism, with

a lost-motion connection so that the mechanism must first move a considerable distance, in either its opening movement or its closing movement, before said lost-motion means is set into motion, said lost-motion means thereupon belatedly responding to the continued movement of said mechanism for forcibly mechanically actuating the disconnecting switching-member from the mechanism with a delayed snap-action so that the disconnecting switching-member opens with a snap-action after the opening of the arc-extinguishing switching-member during the opening operation of the mechanism, and closes with a snap-action after the closure of the arc-extinguishing switching-member during the closing operation of the mechanism, said lost-motion means including means responsive to the movement of said mechanism for engaging the disconnecting switching-member with a sudden striking-movement, so as to apply an effective operating-force thereto, when the mechanism is in an intermediate position during the actuating operation in at least one direction of travel of the mechanism.

9. A circuit-breaker comprising an arc-extinguishing switching-member of a kind such that it is undesirable to leave the circuit-voltage continuously applied thereto after its opening-operation and such that it is undesirable to have the circuit-voltage applied thereto when its switching-contacts are approaching each other during its closing-operation, a serially connected disconnecting switching-member, an operating-mechanism, means responsive to an early part of the opening movement of said mechanism for initiating a separation of the contacts of said arc-extinguishing switching-member, means responsive to an early part of the closing movement of said mechanism for beginning to close the contacts of said arc-extinguishing switching-member, lost-motion means responsive to the continued movement of said mechanism, with a lost-motion connection so that the mechanism must first move a considerable distance, in either its opening movement or its closing movement, before said lost-motion means is set into motion, said lost-motion means thereupon belatedly responding to the continued movement of said mechanism for forcibly mechanically actuating the disconnecting switching-member from the mechanism with a delayed snap-action so that the disconnecting switching-member opens with a snap-action after the opening of the arc-extinguishing switching-member during the opening operation of the mechanism, and closes with a snap-action after the closure of the arc-extinguishing switching-member during the closing operation of the mechanism, and holding means for temporarily holding the disconnecting switching-member in at least one of its operative positions, said lost-motion means including means for nullifying the holding-action of said holding-means and for applying an effective operating-force to said disconnecting switching-member only after said delayed-action time when said lost-motion means becomes effective to forcibly displace the disconnecting switching-member during an actuation of the mechanism.

10. A circuit-breaker comprising an arc-extinguishing switching-member of a kind such that it is undesirable to leave the circuit-voltage continuously applied thereto after its opening-operation and such that it is undesirable to have the circuit-voltage applied thereto when its switching-contacts are approaching each other during

its closing-operation, a serially connected disconnecting switching-member, an operating-mechanism, means responsive to an early part of the opening movement of said mechanism for initiating a separation of the contacts of said arc-extinguishing switching-member, means responsive to an early part of the closing movement of said mechanism for beginning to close the contacts of said arc-extinguishing switching-member, lost-motion means responsive to the continued movement of said mechanism, with a lost-motion connection so that the mechanism must first move a considerable distance, in either its opening movement or its closing movement, before said lost-motion means is set into motion, said lost-motion means thereupon belatedly responding to the continued movement of said mechanism for forcibly mechanically actuating the disconnecting switching-member from the mechanism with a delayed snap-action so that the disconnecting switching-member opens with a snap-action after the opening of the arc-extinguishing switching-member during the opening operation of the mechanism, and closes with a snap-action after the closure of the arc-extinguishing switching-member during the closing operation of the mechanism, and holding means for temporarily holding the disconnecting switching-member in any one of a plurality of closed positions of different degrees of closure, said lost-motion means including means for nullifying the holding-action of said holding-means and for applying an effective operating-force to said disconnecting switching-member only after said delayed-action time when said lost-motion means becomes effective to forcibly displace the disconnecting switching-member during an opening operation of the mechanism.

11. A circuit-breaker comprising an arc-extinguishing switching-member of a kind such that it is undesirable to have the circuit-voltage applied thereto when its switching-contacts are approaching each other during its closing-operation, a serially connected disconnecting switching-member, an operating-mechanism, means responsive to an early part of the opening movement of said mechanism for initiating a separation of the contacts of said arc-extinguishing switching-member, means responsive to an early part of the closing movement of said mechanism for beginning to close the contacts of said arc-extinguishing switching-member, lost-motion yieldable means responsive to the continued movement of said mechanism, with a lost-motion connection so that the mechanism must first move a considerable distance, in either its opening movement or its closing movement, before said lost-motion means is set into motion, said lost-motion means thereupon belatedly responding to the continued movement of said mechanism for forcibly mechanically actuating the disconnecting switching-member from the mechanism with a delayed-action movement, and holding means for temporarily holding the disconnecting switching-member in its open position, said lost-motion means including means for nullifying the holding-action of said holding-means and for applying an effective operating-force to said disconnecting switching-member only after said delayed-action time when said lost-motion yieldable means becomes effective during the course of the closing operation of said mechanism, whereby said disconnecting switching-member closes after the closure of said arc-extinguishing switching-member.

12. A circuit-breaker comprising an arc-extinguishing switching-member, a serially connected disconnecting switching-member, an operating-mechanism, means responsive to an early part of the opening movement of said mechanism for initiating a separation of the contacts of said arc-extinguishing switching-member, means responsive to an early part of the closing movement of said mechanism for beginning to close the contacts of said arc-extinguishing switching-member, lost-motion yieldable means responsive to the continued movement of said mechanism, with a lost-motion connection so that the mechanism must first move a considerable distance, in either its opening movement or its closing movement, before said lost-motion means is set into motion, said lost-motion means thereupon belatedly responding to the continued movement of said mechanism for mechanically actuating the disconnecting switching-member from the mechanism with a delayed-action movement, and holding means for temporarily holding the disconnecting switching-member in any one of a plurality of closed positions of different degrees of closure, said lost-motion means including means for nullifying the holding-action of said holding-means and for applying an effective operating-force to said disconnecting switching-member only after said delayed-action time when said lost-motion yieldable means becomes effective during the course of the opening operation of said mechanism.

13. A circuit-breaker comprising an arc-extinguishing switching-member of a kind such that it is undesirable to leave the circuit-voltage continuously applied thereto after its opening-operation and such that it is undesirable to have the circuit-voltage applied thereto when its switching-contacts are approaching each other during its closing-operation, a serially connected disconnecting switching-member, an operating-mechanism, means responsive to an early part of the opening movement of said mechanism for initiating a separation of the contacts of said arc-extinguishing switching-member, means responsive to an early part of the closing movement of said mechanism for beginning to close the contacts of said arc-extinguishing switching-member, lost-motion yieldable means responsive to the continued movement of said mechanism, with a lost-motion connection so that the mechanism must first move a considerable distance, in either its opening movement or its closing movement, before said lost-motion means is set into motion, said lost-motion means thereupon belatedly responding to the continued movement of said mechanism for mechanically actuating the disconnecting switching-member from the mechanism with a delayed-action movement, and holding means for temporarily holding the disconnecting switching-member both in its open position and in its closed position, said lost-motion means including means for nullifying the holding-action of said holding-means and for applying an effective operating-force to said disconnecting switching-member only after said delayed-action times when said lost-motion yieldable means becomes effective during the operations of said mechanism.

14. A circuit-breaker comprising an arc-extinguishing switching-member, a serially connected disconnecting switching-member, an operating mechanism for opening and closing said arc-extinguishing switching-member, locking-means for positively holding said disconnect-

ing switching-member in at least one of its operative positions, means responsive to the movement of said mechanism for disengaging said locking-means at a predetermined intermediate point in the travel of the mechanism from its position in which the disconnecting switching-member was locked, and means responsive to the movement of said mechanism for subsequently giving said disconnecting switching-member a positive thrust away from its aforesaid locked position during the continued movement of the mechanism.

15. A circuit-breaker comprising an arc-extinguishing switching-member, a serially connected disconnecting switching-member, a relatively high-current-capacity switching-member adapted to be connected in parallel-circuit relation to the two serially connected switching-members, an operating mechanism, means responsive to an early part of the opening movement of said mechanism for opening the high-current-capacity switching-member and initiating a separation of the contacts of said arc-extinguishing switching-member, means responsive to an early part of the closing movement of said mechanism for beginning to close the contacts of said arc-extinguishing switching-member, lost-motion means responsive to the continued movement of said mechanism, with a lost-motion connection so that the mechanism must first move a considerable distance, in either its opening movement or its closing movement, before said lost-motion means is set into motion, said lost-motion means thereupon belatedly responding to the continued movement of said mechanism for mechanically actuating the disconnecting switching-member from the mechanism with a delayed snap-action so that the disconnecting switching-member opens with a snap-action after the opening of the arc-extinguishing switching-member during the opening operation of the mechanism, and closes with a snap-action after the closure of the arc-extinguishing switching-member during the closing operation of the mechanism, mechanical-motion means whereby a relatively large movement of said operating mechanism is accompanied by a relatively small movement of said aforesaid arc-extinguishing switching member when the latter is in its fully closed position, and means responsive to a final part of the closing-movement of said mechanism for finally bringing together the contacts of the high-current-capacity switching-member, whereby the closing movement of said mechanism first closes said arc-extinguishing switching-member and then closes said disconnecting switching-member and finally closes said relatively high-current-capacity switching-member, and the opening movement of said mechanism first opens said relatively high-current-capacity switching-member and then opens said arc-extinguishing switching-member and finally opens said disconnecting switching-member.

16. A circuit-breaker comprising an arc-extinguishing switching-member, a serially connected, non-arc-extinguishing disconnecting-member, and operating-means therefor; characterized by said arc-extinguishing switching-member being of a kind such that it is undesirable to leave the circuit-voltage continuously applied thereto after its opening operation, and such that it is undesirable to have the circuit-voltage applied thereto when its switching-contacts are approaching each other during its closing-operation; and said operating-means having an open-

ing-operation and a closing-operation, means for causing the opening-operation of the operating-means to open the arc-extinguishing switching-member and to temporarily hold it open until the next closing-operation of the operating-means, means for causing a closing-operation of the operating-means to close the arc-extinguishing switching-member and to temporarily hold it closed until the next opening-operation of the operating-means, and lost-motion, snap-action means for automatically operating the non-arc-extinguishing disconnect-member in response to the respective continued opening and closing movements of the aforesaid operating-means, said lost-motion, snap-action means responding at an intermediate point in the opening-movement of the operating-means, and thereupon operating to forcibly mechanically open the disconnect-member with a snap-action substantially independent of the remainder of the opening-movement of the operating-means, and to thereafter temporarily hold the disconnect-member open until the next closing-operation of the lost-motion, snap-action means, the timing being such that the disconnect-member opens after the opening of the arc-extinguishing switching-member, and said lost-motion, snap-action means responding at an intermediate point in the closing-movement of the operating-means, and thereupon operating to forcibly mechanically close the disconnect-member with a snap-action substantially independent of the remainder of the closing-movement of the operating-means, and to thereafter temporarily hold the disconnect-member closed until the next opening-operation of the lost-motion, snap-action means, the timing being such that the disconnect-member closes after the closure of the arc-extinguishing switching-member.

17. The invention as defined in claim 16, characterized by said lost-motion, snap-action means having a thrust-abutment for engaging the non-arc-extinguishing disconnect-member with a sudden striking-movement, so as to apply an effective operating-force thereto, during at least one direction of travel of the lost-motion, snap-action means.

18. The invention as defined in claim 16, in combination with an auxiliary holding-means for temporarily holding the non-arc-extinguishing disconnect-member in at least one of its operative positions, said lost-motion, snap-action means including means for nullifying the holding-action of said auxiliary holding-means when it applies an effective operating-force to said non-arc-extinguishing disconnect-member.

19. The invention as defined in claim 16, in combination with an auxiliary holding-means for temporarily holding the non-arc-extinguishing disconnect-member in any one of a plurality of closed positions of different degrees of closure, said lost-motion, snap-action means including means for nullifying the holding-action of said auxiliary holding-means when it applies an effective operating-force to said non-arc-extinguishing disconnect-member during the next opening-operation.

20. The invention as defined in claim 16, in combination with an auxiliary holding-means for temporarily holding the non-arc-extinguishing disconnect-member in its open position, said lost-motion, snap-action means including means for nullifying the holding-action of said auxiliary holding-means when it applies an effective oper-

ating-force to said non-arc-extinguishing disconnect-member during the next closing-operation.

21. The invention as defined in claim 16, in combination with auxiliary holding-means for temporarily holding the non-arc-extinguishing disconnect-member both in its open position and in its closed position, said lost-motion, snap-action means including means for nullifying the holding-action of said auxiliary holding-means when it applies an effective operating-force to said non-arc-extinguishing disconnect-member during the next operation of the circuit-breaker.

22. The invention as defined in claim 16, characterized by said lost-motion, snap-action means being an over-center yieldable-spring means.

23. A circuit-breaker comprising an arc-extinguishing switching-member, a serially connected, non-arc-extinguishing disconnect-member, a current-carrying shunt-contact adapted to be connected in parallel-circuit relation to the two serially connected members, and operating-means therefor; characterized by said arc-extinguishing switching-member being of a kind such that it is undesirable to leave the circuit-voltage continuously applied thereto after its opening operation, and such that it is undesirable to have the circuit-voltage applied thereto when its switching-contacts are approaching each other during its closing-operation; and said operating-means having an opening-operation and a closing-operation, means for causing the opening-operation of the operating-means to open the shunt-contact and the arc-extinguishing switching-member and to temporarily hold both open until the next closing-operation of the operating-means, getting the shunt-contact open first, means for causing a closing-operation of the operating-means to close the arc-extinguishing switching-member and the shunt-contact and to temporarily hold both closed until the next opening-operation of the operating-means, and lost-motion, snap-action means for automatically operating the non-arc-extinguishing disconnect-member in response to the respective continued opening and closing movements of the aforesaid operating-means, said lost-motion, snap-action means responding at an intermediate point in the opening-movement of the operating-means, and thereupon operating to forcibly mechanically open the disconnect-member with a snap-action substantially independent of the remainder of the opening-movement of the operating-means, and to thereafter temporarily hold the disconnect-member open until the next closing-operation of the lost-motion, snap-action means, the timing being such that the disconnect-member opens after the opening of the arc-extinguishing switching-member, and said lost-motion, snap-action means responding at an intermediate point in the closing-movement of the operating-means, and thereupon operating to forcibly mechanically close the disconnect-member with a snap-action substantially independent of the remainder of the closing-movement of the operating-means, and to thereafter temporarily hold the disconnect-member closed until the next opening-operation of the lost-motion, snap-action means, the timing being such that the disconnect-member closes after the closure of the arc-extinguishing switching-member.
